UNITED STATES PATENT OFFICE.

ANGELO L. ARDIT, OF GRANDVIEW HEIGHTS, OHIO.

MEANS FOR MAKING TERRAZZO FLOORS OR CAST-IN-PLACE TERRAZZO TILE.

Application filed May 29, 1925. Serial No. 33,695.

This invention relates more particularly to composition flooring of the variety known as terrazzo or cast in place terrazzo tile which includes a foundation or undercoat usually of concrete and a superposed thereon layer compounded of small pieces of marble united together with a suitable bond to make a simulation of marble. Heretofore brass strips have been used in laying the terrazzo, such strips being arranged to form panels or blocks and adapted to localize cracking and also for the purpose of developing designs, the upper edges of such strips constituting a leveling gauge to facilitate the application and smoothing of the superposed composition. Such brass strips were left in the floor and constituted an item of considerable expense.

The object of the present invention is to provide means to facilitate the laying of such floors and more especially such floors with decorative borders, and in carrying out my invention I provide molding or forming and kerfing strips preferably of brass, fibre or other suitable hard material which can be removed and reused over and over again thereby greatly reducing the expense as compared with floors in which the aforementioned brass strips are embodied. Because my strips are removable the borders can be made of any different colors to suit the taste and fancy of the owner of the building in which the floor is laid.

The invention is embodied in the examples herein shown and described the features of novelty being finally claimed.

In the accompanying drawing—

Figure 1 illustrates in perspective a short strip having a wide projecting head such as can be used in the larger or wall border in connection with similar long strips for forming blocks surrounded by borders of "cube" designs.

Fig. 2 is a similar view of a long strip such as referred to in the description of Fig. 1 with a transverse tapered web at one end.

Fig. 3 is a similar view of a long strip like that shown in Fig. 2 without the transverse end web.

Fig. 4 is a cross section of such a strip as shown in Figs. 1, 2 or 3 showing it inserted in the cement under coat or foundation and before the top coat or panels are laid.

Fig. 5 is a similar view showing the top coat laid.

Fig. 6 is a similar view showing the strip removed from the two coats.

Fig. 7 is a view similar to Fig. 6 showing the cube border applied and also showing a cushioning strip of paper, felt or other yielding material applied for the purpose of preventing or localizing cracking.

Fig. 8 illustrates a modification of form of strip for permitting the joining of strips to effect continuity of the division of the foundation into blocks.

Fig. 9 is a top plan view of a floor laid according to my invention as it appears at the corner of a room.

Fig. 10 is a plan view of the lower side of the strips as shown in Figs. 1, 2 and 3 arranged to prepare the floor as shown in Fig. 10, said view illustrating how the forms of said strips when so joined are adapted to score continuous lines around a panel and along the wall border.

Referring more particularly to Figs. 1, 2 and 3 the strips are formed of tapering cross section in the vertical web or foundation-penetrating portion 15 the upper or thicker margin being extended or offset laterally to form a head 16 to mold a suitable channel or recess on the bed or undercoat 18 for the reception of so called "cubes" or tile-like blocks to form an ornamental border around the main panels or squares of the terrazzo. The blade 15 is made tapering to permit its easy withdrawal from the work and it is also preferable that the lateral face of the head at 17 be slightly beveled or inclined from the lower corner upward and outward from the portion 15 to permit the withdrawal of that portion of the strip from the work without fracturing the edges of the panels. Some of the strips, such as shown in Fig. 2, are formed with transverse penetrating portions 15^a constituting angular continuations of the longitudinal portions.

In Figs. 4, 5, 6 and 7 is illustrated the method of using the strips as shown in Figs. 1, 2 and 3.

In practice the foundation or undercoat 18 of the usual material and suitable thickness is first laid and leveled and before it has hardened the tapered blades 15 are shoved into it as depicted in Fig. 4. When the strips are so placed the head portions constitute the sides of molds for receiving and determining the thickness of the plastic

cast in place panels 19 as shown in Fig. 5 the upper surface of said heads forming guides to aid in leveling and smoothing the panels. After the blocks or panels 19 have 5 sufficiently hardened so as not to slack down but before they have completely hardened the strips are removed leaving linear cavities having a cross section like that depicted in Fig. 6. To facilitate the removal 10 of said strips their head portions can be made with threaded sockets into which are turned screw eyes 20 or other instruments adapted to be taken with the fingers of the hand or to receive a suitable lifting tool. 15 After the floor is molded as illustrated in Fig. 6 and has completely hardened a strip of paper or roofing felt 21 may be placed in the cut supplemented with a filling of 20 plastic material 22 to the level of the under coat. The space formed by the head is then filled with the "cubes" or tile-like blocks 23 of the same or different colors laid in with a suitable cementing liquid to hold them solidly in place. 25 A fraction of finished floor at the corner of a room as formed by the strips illustrated in Figs. 1, 2 and 3 and the method of using them as described and illustrated in connection with Figs. 4, 5, 6 and 7 is shown 30 in Fig. 9 where corresponding characters of reference 21, 22 and 23 have been applied to designate the paper or felt the plastic material of the panels and the "cubes" respectively. The narrow panels 23 and small squares at the corners in this view form a wide border around the walls of the room while the large squares form the main body of the floor the latter being bordered by the 35 lines of "cubes." 40 Fig. 10 illustrates the appearance of the floor forming strips as viewed from the lower side when arranged to form such a floor as illustrated in Fig. 9 it being noted that the transverse webs 15^a align with the main webs 15 to form practically continuous dividing members around the large interior panels. 45 The forms of the parts can be changed without departing from the gist of the in-

vention as claimed; for example instead of 50 providing the transverse web 15^a at an end of a strip such as indicated in Fig. 2 substantial continuity of the penetrating portion of the strip at corners can be effected by cutting away a portion of the head of 55 one strip as indicated at 25 in Fig. 8 so that the penetrating web at the cut-away end can have superposed on it the projecting head of another strip in any desired angular relation with the penetrating webs contacting 60

With my construction the strips can be so arranged that some or all of the panels can be made of any desired polygonal design, which will be of especial advantage in forming ornamental central panels for the 65 floor.

What I claim is:

1. Means to aid in the laying of plastic terrazzo floors and other surfaces which include panels and ornamenting lines of cubes 70 adjacent thereto, said means consisting of a removable strip having a tapered blade-like concrete-bed-penetrating portion to form a panel-cracking localizing recess in said bed, and a head portion projecting laterally 75 from the thicker edge of said strip adapted to form a side of a panel mold and also to leave a seat upon said bed adjacent the panel for the reception of said cubes.

2. Means to aid in the laying of plastic 80 terrazzo floors and other surfaces which include panels and ornamenting lines of cubes adjacent thereto, said means consisting of a removable strip having a tapered blade-like concrete-bed penetrating portion to 85 form a panel-cracking localizing recess in said bed, and a head portion projecting laterally from the thicker edge of said strip adapted to form a side of a panel mold and 90 also to leave a seat upon said bed adjacent the panel for the reception of said cubes, said penetrating blade having a fractional portion similar in form to the blade standing at an angle thereto below said laterally 95 projecting head portion to extend the panel cracking localizing recess around the corner of a panel.

ANGELO L. ARDIT.
